UNITED STATES PATENT OFFICE.

RAGNAR L. NILSSON AND ELVYN C. CHMEL, OF MINNEAPOLIS, MINNESOTA.

ELECTRIC-GLOBE REMOVER.

Application filed June 9, 1923. Serial No. 644,437.

This invention relates to improvement in implements for inserting and extracting electric light bulbs, and more particularly to a mechanically operated device which will be especially adapted for use in substituting new bulbs for burned out ones in large electric signs.

One of the objects of the invention is to provide an implement of this character which may be employed to hold a bulb and which can be quickly operated to clutch the bulb so that it will be screwed into the electric socket, and which may be just as easily operated to extract the bulb from the socket.

Other objects of the invention will appear upon consideration of the following detailed description and accompanying drawings, wherein:

Figure 1 is a side elevation of the device constructed in accordance with our invention.

Figure 2 is a plan view of the bulb gripping portion.

Figure 3 is a cross section taken on the line 3—3 of Figure 1.

Figure 4 is a detailed sectional view showing a modified arrangement of the mechanism.

Figure 5 is a detailed view of one of the bulb gripping elements.

Figure 6 is a side view of an attachment for use in extracting the bases of broken bulbs from electric light sockets, and

Figure 7 is a plan view of the same.

Referring to the drawings by numerals, the pole 1 may be of any desired length and has its upper end provided with a bevelled gear 2 rigidly fixed to the pole so that it may turn when the pole is turned. An elongated pintle 3 is formed by an extension on the end of the pole beyond the gear 2 and this pintle is adapted to receive a sleeve 4 which is provided with an angular extension 5 carrying an angular pintle 6.

The upper end of the pintle 3 extends upwardly beyond the upper end of the sleeve 4 and is adapted to receive a beveled gear 7 which is fastened to the pintle by a movable locking pin 8 as shown in Figure 4.

The hub 9 of the gear 7 is provided with ears carrying pivot pins for pivotally receiving the arms 10 which extend radially from the hub of the gear as shown in Figure 3 of the drawings. These arms 10 are each provided with a gripping finger 11 which is shaped to fit the electric light bulb

and is provided with suitable pads 12 at the point where the fingers engage the bulb.

Each of the fingers 11 are adjustably carried by an arm 10 so that the fingers may be slid towards or away from each other to permit the same to engage electric light bulbs of different sizes. A thumb nut 11^a is carried by each finger for clamping the same in the desired position on the arm 65 upon which the finger is mounted. Near their pivoted ends, the arms 10 are provided with slots 13 through which the pins 14 are extended and coil springs 15 are interposed between the gear 7 and the arms 10 and surround the pins 14 as shown to exert a spring pressure on the arms whereby the fingers 11 will effectively grip the electric light bulb. A stop pin 14^a is passed through the free end of each pin 14 to limit the inward 70 movement of the fingers so as to permit said fingers to be readily slipped over an electric light bulb.

When the parts are assembled in the position above described, it will be obvious that a turning movement imparted to the pole 1 will be transmitted to the gear 7, and since this gear is connected to the arms 10 which carry the fingers 11, a turning movement will be imparted to the bulb so that it may be 80 either inserted or extracted. This arrangement is effectively employed for inserting and extracting bulbs in ceiling fixtures.

When the device is to be used as illustrated in Figure 1, the gear 7 will be removed from the pintle 3 and placed on the pintle 6 so that the teeth of the gear 7 will mesh with the teeth of the gear 2. In this arrangement, the gear 7 is not keyed to the pintle 6 but is free to rotate thereon, and since the arms 90 10 and fingers 11 are carried by the gear 7, it will be obvious that rotary motion imparted to the bulb will be transmitted to the gears, thus causing the turning motion necessary for inserting and extracting the bulbs. 95

For opening and closing the gripping fingers 11 a flexible cord 17 is provided which has one end fixed to one of the arms 10 so that a pull on the cord or wire 17 will cause one of the arms 10 to swing on its pivot and 100 open the gripping fingers 11.

The attachment shown in Figures 6 and 7 of the drawings comprises a triangular base ring 20 and three gripping fingers 21 attached to the corners of the ring 20 and arranged to form connecting pins 22 adapted 110 to be received in conveniently arranged open-

ings 23 in the fingers 11. The upper ends of the fingers 21 are connected to rubber gripping members 24 which are adapted to engage the inside of the base of a broken bulb whereby the same may be turned and extracted from the socket.

What we claim is:

1. A bulb inserting and removing implement comprising a pole having a pintle fixed at its end, a gear wheel fixed to the pole at the inner end of the pintle, a sleeve loosely mounted upon the fixed pintle and having an angularly disposed pintle, a second gear wheel transferable from one pintle to the other and adapted to mesh with the first mentioned gear wheel when applied to the sleeve

pintle, bulb gripping fingers carried by the second mentioned gear wheel, and means extending along the pole for spreading the fingers with relation to each other.

20

2. In a bulb inserting and removing implement a gear wheel, arms pivoted thereon, pins mounted upon the wheel and passing through the arms, springs coiled about the pins and interposed between the wheel and the arms and bulb gripping fingers carried by the arms.

In testimony whereof, we affixed our signatures.

RAGNAR L. NILSSON.
ELVYN C. CHMEL.
